(57) **CLAIM**

The ornamental design for a portion of a keyboard, as shown and described.

DESCRIPTION

FIG. 1 is a top front perspective view of a portion of a keyboard showing my new design;

FIG. 2 is a top view thereof;

FIG. 3 is a left side view thereof; and,

FIG. 4 is a front view thereof.

The broken line showing of the remainder of the keyboard forms no part of the claimed design.
